UNITED STATES PATENT OFFICE.

CYRIL J. ATKINSON, OF MILWAUKEE, WISCONSIN, ASSIGNOR TO
INTERNATIONAL HARVESTER COMPANY, A CORPORATION OF
NEW JERSEY.

GAS-PRODUCER.

No. 841,100.

Specification of Letters Patent.

Patented Jan. 15, 1907.

Application filed May 7, 1906. Serial No. 315,608.

To all whom it may concern:

Be it known that I, CYRIL J. ATKINSON, a citizen of Great Britain, residing at Milwaukee, county of Milwaukee, and State of Wisconsin, have invented certain new and useful Improvements in Gas - Producers, of which the following is a specification, reference being had to the accompanying drawings, forming a part thereof.

10 My invention relates to means for automatically regulating the supply of water to the vaporizer of a gas-producer in accordance with the demand for gas therefrom, and particularly to that type commonly called 15 "suction-producers," wherein the flow of air to the retort to aid combustion is induced by a suction action of the engine caused by the forward stroke of the piston producing a partial vacuum in the cylinder in drawing in 20 its charge.

Referring to the accompanying drawings, Figure 1 represents an elevation of a gas-producer having my invention embodied therein. Fig. 2 is a sectional elevation of a 25 feed-water cup.

Similar reference-numerals designate like parts throughout both views.

1 represents a retort. 2 is a gas-conduit communicating therewith and leading to the 30 scrubber and engine. (Not shown.) 3 is a vaporizing - chamber surrounding the gas-conduit and receiving heat therefrom. 4 is a pipe connecting the vaporizing-chamber with the retort. 5 is an opening in the wall 35 of the vaporizing-chamber for the purpose of admitting air thereto, and 6 is a swinging gate-valve adapted to control the size of said opening. 7 is a water-tank in which the 40 water is maintained at a fixed level by being connected with a source of water-supply by any preferred means. 8 is a pipe connection between said tank and the bottom of a feed-water cup 9. The cup is preferably cylindrical in form and air-tight and having an 45 outlet therefrom comprising a pipe 10, passing through the bottom of the cup and adapted to conduct the water to the upper part of the vaporizing-chamber. The pipe 8 extends upward through the body of the cup to 50 a plane slightly below the top thereof and is provided with one or more slots 11 in its wall, that extend from the upper end of the pipe to a plane slightly above the bottom of the cup, the combined areas of the slots being

approximately equal to that of the pipe. 55 The constant-level tank and the feed-cup are so located relatively to each other that a head of water is maintained in the pipe 8 approximately level with or slightly below the lower ends of the slots in the feed-pipe when 60 the plant is at rest. At each suction-stroke of the engine air is drawn into the vaporizing-chamber through the opening 5, and also through the pipe 10, communicating with the feed-cup 9, and causes a partial vacuum 65 in said cup. As the pressure of air is reduced in the feed-cup the water will rise, and more or less of it will flow through the slots and pipe 10 to the vaporizer, the quantity being proportionate with the degree of vacuum 70 in the feed-cup and the latter with the speed of the engine.

To maintain a uniform percentage of moisture at varying speeds of the engine, it is desirable that the supply of water supplied to 75 the vaporizer should not only be proportionate with the speed of the engine, but should vary as rapidly as the speed changes—that is, the variation in the requirement should as quickly have a variation in effects to meet 80 the requirement, and such is the result attained by the mechanism described—that is, the greater the speed of the engine the greater will be the degree of vacuum in the feed-cup, and consequently the flow of water therefrom 85 to the vaporizer will be greater.

The inlet for air into the vaporizing-chamber may be more or less closed or regulated by the swinging gate, as required to further control the water-supply.

What I claim, and desire to secure by Letters Patent, is—

1. A suction gas-producer comprising, in combination, a retort, a gas-conduit leading therefrom, a vaporizing-chamber adapted to receive heat from said gas-conduit, said chamber having an air-inlet and a conduit communicating with said retort, means for admitting water into said chamber, said means comprising a constant-level water- 95 tank, an air-tight feed-water cup, a pipe connection between said tank and cup, said connection extending upward within said cup and provided with lateral openings therein, the combined areas of the openings being 100 approximately equal to that of said pipe connection whereby said connection has a variable overflow within said cup proportionate 105

with the degree of vacuum formed therein and caused by the flow of air to said producer, and a water-conduit connecting said cup with said vaporizing-chamber.

5. 2. A suction gas-producer comprising, in combination, a retort, a gas-conduit leading therefrom, a vaporizer adapted to receive heat from said gas-conduit, said vaporizer having an air-inlet and a conduit communicating with said retort, means for admitting water into said vaporizer, said means comprising a constant-level water-tank, an air-tight feed-water cup, a pipe connection between said tank and cup, said pipe extending

vertically within the cup and having one or more slots therein, the combined areas of the slots being approximately equal to that of said pipe connection, whereby a variable overflow of water is permitted within said cup proportionate with the degree of vacuum formed therein and caused by the flow of air to said producer, and a water-conduit connecting said cup with said vaporizing-chamber.

CYRIL J. ATKINSON.
